WOBBLE PLATE LAUNDRY MACHINE

Thomas R. Smith, Newton, Iowa, assignor to The Maytag Company, Newton, Iowa, a corporation of Delaware

Application December 27, 1955, Serial No. 555,322

9 Claims. (Cl. 68—131)

This invention relates to a wobble plate agitator for clothes washing machines. In the invention further disclosed hereinafter, a meniscus shaped agitator having a convex upper surface and a generally concave lower surface is provided with a depending flexible sleeve molded integrally with the agitator proper. This flexible sleeve is clamped to certain bearing structure mounted in the bottom of a clothes basket enclosing the agitator to thereby form a liquid tight seal for an agitator power shaft journaled in that bearing structure and provided with a bent terminal portion which extends upwardly into the clothes basket through the resilient sleeve and into a bearing formed in the agitator.

Rotation of the agitator power shaft in either direction causes the agitator to gyrate in a wobbling motion with its thinner peripheral rim moving primarily in a vertical path and flexing in that direction to produce a pumping action of the fluid within the clothes basket. A cleansing of the fabrics in the fluid is achieved by the toroidal currents generated around the agitator through this agitator movement. In the embodiment disclosed herein fluid is extracted from the clothes within the basket following the washing operation through a centrifugal extraction process by rotating a tubular spin shaft depending from the clothes basket and journaling the agitator power shaft.

While it is recognized that agitators of the wobble plate type may be rotated in either direction and require no gear trains or other motion converting units necessary to achieve a reciprocating or oscillating motion now common to agitators of domestic type washing machines, the wobble plate agitator of this invention has further advantages. This agitator is preferably molded of one piece and not only provides the necessary washing action required to properly cleanse fabrics but also provides a liquid tight seal for the agitator shaft and its bearings to guarantee a service life free of damage caused by water seepage into these parts. The agitator unit is simple in construction, effective in operation and economical in manufacturing and assembly operations.

Through the use of the meniscus shaped agitator formed of a flexible material, as further disclosed herein, an additional pumping action is achieved by the flexing of the peripheral rim of the agitator as it progresses through its wobbling movement. These and other advantages, which will be more apparent when reference is made to the accompanying drawings and following description, form the objects of this invention.

Referring now to the drawings:

Figure 1 is a side elevation, partially in section, showing a washing machine embodying my invention;

Figure 2 is an enlarged sectional view taken on line 2—2 of Figure 3 to show the details of the agitator, the connection of the agitator power shaft to the agitator, and the seal formed between the agitator and the bearing structure journaling the agitator power shaft; and

Figure 3 is a plan view of the agitator taken on line 3—3 of Figure 1.

2

In the accompanying drawings there is shown a base frame 10 mounted on adjustable feet 11 and provided with a supporting dome 12 rising out of a centrally located depression 13 in the base frame 10. Dome 12 serves as a mounting for a drive assembly 14 such as that disclosed in the John D. Goodlaxson application, Serial No. 505,231, filed May 2, 1955, and assigned to the same assignee as that of the instant application.

Base frame member 10 also supports the upended reversible motor 15 and water pump 16 which, like drive assembly 14, is driven by motor 15 through belt 17 on the underside of base frame 10. Numeral 19 designates the groove of pulley 18 which serves as the input member for the drive assembly 14.

Cabinet 21, attached to and enclosing base frame 10 together with the drive and tub assemblies supported thereby, is provided at its upper end with a depending annular flange 22 defining an access opening into the washing machine apparatus which is normally covered by access door 24.

In Figure 1 it can be seen that dome 12 in base frame 10 is provided with friction pads 26 at its periphery adjacent the opening 27 in its uppermost portion.

An umbrella-like support member 28 rests on these friction pads 26 and is provided with three equally spaced ears 29 for three centering springs 31 which may be attached directly to base frame 10 or fastened to brackets 32 connected to the base frame 10. This arrangement centers support member 28 on dome 12 and restrains it from rotation.

Threaded into the umbrella support member 28 is member 34 of substantially frusto-conical configuration which serves as a housing for drive assembly 14 of the previously identified Goodlaxson application, Serial No. 505,231. Housing member 34 cooperates with umbrella support member 28 by gripping the outer race of a thrust bearing 35 which is provided with a tapered inner race. Mating with and seated in this tapered inner race of bearing 35 is the spin tube or shaft 37 which journals a power shaft 38 also extending into the drive assembly 14. With this construction all weight placed on the spin tube 37, housing 34 and on umbrella member 28 may be used to an advantage to provide ample frictional forces between umbrella member 28 and the friction pads 26 for dampening nutational movements of the shafts 37 and 38 relative to dome 12 while permitting rotational movement of spin tube 37 in thrust bearing 35.

While the details of the Goodlaxson drive assembly forming the basis for the previously identified application, Serial No. 505,231, are not essential to the construction of the instant invention, its operation can be briefly explained for environmental purposes. Upon energization of motor 15 in a direction to rotate pulley 18 in a counterclockwise direction as viewed from the bottom of Figure 1, power shaft 38 is rotated in this same direction while spin shaft 37 is held against rotation by appropriate braking mechanism within housing 34. Upon reversal of motor 15, spin shaft 37 is released for rotation to allow both of shafts 37 and 38 to be spun in unison in a clockwise direction.

With the drive and support construction set forth above, it can be seen that shafts 37 and 38 may be selectively rotated as determined by the direction of rotation imparted to pulley 18 while permitting their nutation about a vertical axis at all times. In the modification set forth in the accompanying drawings, shafts 37 and 38 nutate on a point determined by the intersection of the vertical axis of rotation with a horizontal plane bisecting groove 19 of pulley 18.

With reference to the tub assembly enclosing the agitator forming the invention of the instant application, it

will be noted that umbrella support member 28 is provided with recessed upstanding lugs 41 spaced equally from each other and alternately around member 28 with respect to the ears 29. While not entirely obvious from Figure 1, it should be apparent from this description that there are three lugs 41 spaced 120° from each other each of which is 60° removed from an adjacent ear 29.

Fastened within the recessed lugs 41 by connectors 42 are the three tub brace members 43 which are, in this embodiment, of channel-like cross section. Brace members 43 extend outwardly and upwardly from umbrella support member 28 to join the non-rotatable tub 44 through tub connectors 45 to form an inverted tripod support for tub 44. The tub 44 is provided with a bottom wall 47 in which is formed a C-shaped gutter 48 having its lowermost portion converging into the drain outlet 49 which in turn communicates with water pump 16 through the flexible drain hose 51.

The imperforate cylindrical side wall 52 of tub 44 includes a slightly enlarged rim 53 on its uppermost portion before terminating in an outwardly directed flange. Resting on the flanged upper edge of side wall 52 is a spherical segmental member 55 having a flanged periphery and a rolled inner edge. Member 55 forms a water tight seal with wall 52 as these members are gripped by the rubber sealing band 56 encompassing the peripheral flanges of wall 52 and the segmental member 55.

Resting on the upper surface of member 55 and having its inner cylindrical portion fastened to the outer periphery of the depending flange 22 is the combined water and vapor seal 58 which prevents the escape of either water or steam from tub 44 during normal use of the machine utilizing this construction.

Referring now to Figures 1 and 2 it can be seen that spin tube 37 extends upwardly from drive assembly 14 and passes through the babbitt bearing liner 61 on the self aligning bearing sleeve 62 which is fitted into a centrally located flanged opening in the bottom wall 47 by a squeeze fit with a tubular rubber member 63 bonded to the periphery of the cylindrical sleeve 62. Sleeve 62 is provided with an annular oil reservoir 64 for the wicking material 65 which is fitted into the bores communicating with the reservoir 64 and the spin tube 37 at the upper end of sleeve 62.

Since there is relative movement between the non-rotating tub 44 and the spin tube 37, tub 44 is provided with a bellows type seal 68 which is pressed against the bottom wall 47 by means of a coil spring 69 within that seal. The uppermost portion of seal 68 is provided in turn with a carbon nosed sealing ring 71 which is pressed upwardly by the coil spring 69 against the lower side of a tubular basket mounting stem 72.

Basket mounting stem 72 slides onto the upper end of spin tube 37 and is held in position on that tube by means of a pin 73 inserted in the upper end of spin tube 37. While the preferred construction utilizes two diametrically opposed pins to hold the basket mounting stem 72 on shaft 37, only one of these pins is illustrated in Figure 2 in order to simplify that drawing and to show more clearly the additional basket supporting function of the mounting stem 72.

Basket mounting stem 72 includes a frusto-conical shoulder 77 which supports the basket 78 having a bottom wall 79 and a side wall 81. Bottom wall 79 is perforate at its lowest elevation for passage of liquid and sediment into the tub 44 and has a slope conforming substantially to the bottom wall 47 of the outer tub 44. Side wall 81 includes a main perforate cylindrical portion and an upper imperforate portion which slopes inwardly towards its axis of rotation to form a seat for balancing ring 82 within rim 53 before terminating in a rolled edge 84 which defines the access opening into the tub assembly.

While the weight of basket 78 is supported on the mounting flange 77, basket 78 is prevented from tipping,

tilting or turning on that flange by means of the large nut 80 which is threaded on the upper part of the basket mounting stem 72 in order to wedge the conical portion of wall 79 against the flange 77. In addition to wedging basket 78 on flange 77, nut 80 forces the centrally located horizontal flange 83 of basket 78 against a small sealing gasket 85 located immediately below the latter flange to provide an air-tight seal between basket 78 and the basket mounting stem 72.

Referring now to the novel type agitator construction forming the invention of this application, it will be noted that the agitator power shaft 38, which extends upwardly from the drive assembly 14, passes upwardly through a bearing 91 which is seated in the recessed upper end of spin tube 37. From bearing 91 power shaft 38 extends through a thrust collar 92 fastened to power shaft 38 by means of a pin 93 to prevent any axial movement of that shaft in a downward direction. The terminal portion 94 of power shaft 38 is bent slightly from the vertical axis and is journaled in a needle bearing 95 housed within a bearing retainer 96 which in turn is contained within a mating bore of the wobble plate agitator 97. Bearing disc 98 fitted into the upper end of bearing retainer 96 and abutting the end of shaft 38 prevents centralized wear on agitator 97 by rotation of that shaft.

Wobble plate agitator 97 is formed substantially in the shape of a meniscus from rubber or a similar resilient material and has a convex upper surface 101 and a generally concave lower surface 102. These surfaces 101 and 102 cooperate with each other to define a rather thick durable central portion which encloses bearing retainer 96 as well as defining a thinner more flexible rim 103.

Molded integrally with the main meniscus portion of agitator 97 is the sealing sleeve 104 which extends downwardly past the bearing retainer 96 and well over the upper end of mounting stem 72 where it is mechanically sealed by means of the clamp ring 105 encompassing the lower end of sleeve 104. In the preferred embodiment illustrated sleeve 104 is molded in a symmetrical mold with a preformed slightly bulbous section 106 to achieve a flexible bellows type action during the gyration of agitator 97 upon the rotation of agitator power shaft 38.

In this embodiment the terminal shaft portion 94 is inclined slightly from the vertical so that each revolution of power shaft 38 moves each part of the rim 103 through a small arc. Since most of the movement of rim 103 is in a vertical direction due to the slight lateral movement of agitator 97, each point on rim 103 describes an ellipse having a vertical major axis.

It is within the teaching of this invention to vary the inclination of the shaft portion 94 with respect to the vertical or to replace the bent shaft portion 94 with an offset crank in order to eliminate or reduce the lateral movement of agitator 97 or to increase the vertical displacement of rim 103. It should be noted here that regardless of the inclination of shaft portion 94, shaft 38 and its bearings 91 and 95 will be well protected from damage from water seepage by means of the flexible sealing sleeve 104.

In operation, over typical agitation and spin periods, the fabrics to be cleaned are inserted into basket 78 through the access openings defined by depending flange 22 and the rolled edge 84. A suitable detergent is then added to the water placed within the tub 44 by a water supply system not shown and not forming a part of this invention. Though a valve may be used in the drain hose 51 to prevent the washing fluids from draining from the tub 44, the water may be retained within tub 44 in this illustrated embodiment by merely maintaining the external drain hose (not shown) attached to the outlet of pump 16 at a higher elevation than elevation of the water contained within tub 44.

During the tub filling period when the liquid rising within tub 44 has covered the perforations in the sloping

basket bottom wall 79, air will be trapped between the bottom walls 79 and 47 due to the sealing action of the bellows type seal 68 and the air-tight connection between basket 78 and the basket mounting stem 72. This normally prevents fluids from contacting the bellows seal 68 or the carbon nose ring 71.

After tub 44 has been filled with the selected quantity of washing fluid, the reversible motor 15 is then energized through a control system (not shown) to rotate the drive pulley 18 in a counterclockwise direction as viewed from the bottom of Figure 1. Through the use of the drive assembly illustrated, rotation of pulley 18 at a speed of approximately 600 R. P. M. in a counterclockwise direction imparts the same angular velocity and directional rotation to power shaft 38 while the braking mechanism provided within the drive assembly 14 restrains spin tube 37 against rotation with power shaft 38. From this, it will be apparent from Figure 2 that rotation of power shaft 38 causes the bent shaft portion 94 to move agitator 97 in a gyratory path while the anchoring clamp 105 which fastens the sealing sleeve 104 to the braked stationary mounting stem 72 will restrain agitator 97 from rotation and cause it to assume a wobbling motion necessary to achieve the desired washing action.

For satisfactory washing action the water level within tub 44 should cover the upper surface 101 of agitator 97 to allow the water current inducing the lower surface 102 to effectively propel the water downwardly and away from the underside of the agitator 97. Since the water currents as set up by the wobbling agitator are strongest in the region below and immediately around the agitator, a more vigorous and more thorough washing action of the clothes in this zone is achieved than has been gained in the past by earlier types of wobble plate agitators incorporating a shielded construction preventing clothes from being agitated in this zone.

The particular shape of agitator 97 is unique in that it produces fluid currents which go down and away from agitator 97 in a toroidal action around agitator 97. While rim 103 moves up and down in a primarily vertical direction, the water currents generated by the movement of agitator 97 are primarily unidirectional due to the use of the meniscus shaped agitator. This particular current path is achieved as the curved upper surface 101 encounters less resistance in its upward travel than does the cup-like lower surface 102 in its downward travel during the wobbling movement of the agitator 97. Consequently, a greater pumping action results during the downward movement of rim 103 than during its upward movement.

While the shape of the agitator 97 accounts for its novel pumping function, the impulsing action may be accented through the use of a resilient material such as rubber or the like as illustrated in the accompanying drawings. Such a resilient material allows the agitator rim 103 to buckle downwardly and thus decrease the fluid propelling area when the rim 103 is moved upwardly whereas a downward movement of rim 103 causes the cup-like surface 102 to flex outwardly to a greater diameter to thereby increase the effective pumping area.

The wobbling action of agitator 97 forces the cleaning fluid through the fabrics within the basket 78 and separates impurities held by them. The larger and heavier particles such as sand and sediment fall to the bottom of the basket 78 where they pass through the holes in the bottom basket wall 79 in the lowermost portion of that wall. This agitation of fluid within tub 44 also causes these heavier particles to work their way down the sloping tub wall 47 and into the gutter 48 around the periphery of bottom wall 47. Once in this gutter, these particles continue to seek a lower elevation in the agitator fluid and eventually find their way into the deepest part of gutter 48 where they pass into the drain outlet 49 and then into the drain hose 51.

Upon completion of the agitation cycle and the initiation of the spin or liquid extraction period, motor 15 is reversed causing the water pump 16 and the drive assembly pulley 18 to reverse their directions also. When driven in this direction, water pump 16 is permitted to pump the washing fluid together with the accumulation of sand and sediment from tub 44 through its drain connections. This reversal of motor 15 also causes the braking mechanism within drive assembly 14 to release the spin tube 37 for rotation in unison with the power shaft 38. Rotation of the spin tube 37 imparts a similar rotary movement to the basket mounting stem 72 and consequently to the clothes basket 78 which centrifugally extracts fluids through its perforate side wall 81. While these rotating members are maintained in balance above the critical speed of this apparatus by means of the balancing ring 82, it should be noted that the lateral deviation of basket 78 with respect to the non-rotating outer tub 44 is prevented by means of the self-aligning radial bearing provided in the bottom of tub wall 47.

At the end of the spin dry operation motor 15 is stopped causing the drive assembly 14 to quickly terminate the rotation of both of shafts 37 and 38. Though these periods may be repeated and rinse periods added, this terminates the spin period of an illustrated operational cycle.

While I have illustrated the operation of my novel type agitator in cooperation with the tub assembly disclosed and with a specific reversible drive assembly, it should be realized that this agitator may be used with other types of tub assemblies and need not be used with a reversible drive assembly.

In summary then, it will be noted that the disclosed agitator provides a simple, economical and effective means for cleansing soiled fabrics. It eliminates the conventional motion converting units necessary to achieve a reciprocating or oscillating motion common to agitators now common in domestic type laundry machines and it is relatively simple to manufacture, assemble and service. In addition, it incorporates a unique sealing sleeve for sealing the agitator power shaft from any water damage.

While only one embodiment of my invention has been illustrated in the accompanying drawings, it is deemed within the teaching of my invention to invert the meniscus shaped agitator or to provide a multiple stacking of such agitator discs. Furthermore, it is realized that slightly different wobbling movements may be obtained by the use of an offset crank rather than by the use of a bent shaft as illustrated in this embodiment. It is therefore my intention not to be limited to the disclosed embodiment but by the appended claims.

I claim:

1. A washing device comprising, a tub, first bearing means in said tub, a power shaft journalled in said first bearing means, a terminal portion on said shaft positioned in said tub in an oblique relationship to the longitudinal axis of said shaft in said first bearing means, means for turning said shaft, a wobble plate agitator within said tub, said agitator having a central portion provided with second bearing means receiving said terminal portion, said agitator being further provided with a sleeve formed integrally with said central portion in a contiguous relationship to said second bearing means and depending from said central portion to provide a seal for said shaft and for said first and second bearing means, and means anchoring said sleeve to restrain said agitator against turning with said shaft.

2. A washing device comprising, a tub, first bearing means in said tub, a power shaft journalled in said first bearing means, a terminal portion on said shaft positioned in said tub in an oblique relationship to the rotational axis of said shaft in said first bearing means, means for rotating said shaft, a wobble plate agitator within said tub, said agitator having a central portion provided with second bearing means receiving said terminal portion,

said agitator being further provided with a flexible sleeve formed integrally with said central portion in a contiguous relationship to said second bearing means and depending from said central portion to form a liquid tight seal for said shaft and for said first and second bearing means, and means anchoring said sleeve on said first bearing means to restrain said agitator from rotation with said shaft.

3. A washing device comprising, a tub, first bearing means in said tub, a power shaft journalled in said first bearing means, a terminal portion on said shaft positioned in said tub in an oblique relationship to the rotational axis of said shaft in said first bearing means, means for rotating said shaft, a resilient one-piece wobble plate agitator within said tub, said agitator having a central portion provided with second bearing means receiving said terminal portion, said agitator being further provided with a flexible sleeve formed integrally with said agitator and in a contiguous relationship with said second bearing means, said sleeve depending from said central portion and anchored on said first bearing means to provide a water-tight seal for said shaft and said first and second bearing means and to restrain said agitator against rotation with said shaft.

4. A washing device comprising, a tub, bearing means in said tub, a power shaft journalled in said bearing means, a terminal portion on said shaft positioned in said tub in an oblique relationship to the rotational axis of said shaft in said bearing means, means for rotating said shaft, a resilient meniscus-shaped wobble plate agitator within said tub, said agitator having a central portion with a bearing receiving said terminal portion, said agitator being further provided with a flexible sleeve formed integrally with said agitator, said sleeve cooperating with said central portion to provide a mounting for said bearing, said sleeve depending from said central portion to form a water-tight seal for said shaft and said bearing means, and means anchoring said sleeve to restrain rotation of said agitator with said shaft.

5. A washing device comprising, a tub, bearing means in said tub, a power shaft journalled in said bearing means, a terminal portion on said shaft positioned in said tub in an oblique relationship to the rotational axis of said shaft in said bearing means, a meniscus-shaped wobble plate agitator within said tub, said agitator having convex and concave surfaces cooperating with each other to define a central hub portion and a resilient peripheral rim, a bearing in said central hub portion receiving said terminal portion, said agitator being further provided with a flexible sleeve formed integrally with said central portion and depending therefrom to form a water-tight seal for said shaft and said bearing means, said sleeve cooperating with said central portion to provide a mounting for said bearing, means for rotating said shaft in said bearing means to impart an undulating movement to said agitator, and means anchoring said sleeve to restrain said agitator against rotation with said shaft.

6. A washing device comprising, a tub, bearing means in said tub, a power shaft journalled in said bearing means, a terminal portion on said shaft positioned in said tub in an oblique relationship to the rotational axis of said shaft in said bearing means, a meniscus-shaped wobble plate agitator adapted to be submerged in fluid placed within said tub, said agitator having an upper convex surface and a lower concave surface cooperating to define a central hub portion and a resilient peripheral

rim, a bearing in said central hub portion receiving said terminal portion, said agitator being further provided with a flexible sleeve formed integrally with the said central portion and depending therefrom to cover and seal said shaft and said bearing means from fluid surrounding said agitator, said sleeve cooperating with said central portion to provide a mounting for said bearing, means for rotating said shaft in said bearing means to impart an undulating movement to said agitator and a flexing movement to said rim, and means anchoring said sleeve on said bearing means to restrain said agitator against rotation with said shaft.

7. In a washing machine, a tub provided with a bearing therein, a meniscus-shaped wobble agitator positioned within said tub, a revoluble shaft journalled in said bearing and provided with a terminal portion inclined from the longitudinal axis of said bearing and extending into said tub, a bearing retainer sleeve mounted in said agitator, bearing means in said bearing retainer sleeve for receiving said terminal portion to effect a wobbling movement of said agitator during rotary movement of said shaft, a flexible sealing sleeve joined to and depending from said agitator toward said tub, said sealing sleeve contiguously encircling said bearing retainer sleeve and having a depending end encompassing said bearing in said tub to provide a watertight seal for said last named bearing.

8. In a washing machine, a tub provided with a bearing therein, a meniscus-shaped wobble agitator positioned within said tub, a revoluble shaft journalled in said bearing and provided with a terminal portion inclined from the longitudinal axis of said bearing and extending into said tub, said agitator including a central portion mounting a bearing retainer sleeve therein, bearing means in said bearing retainer sleeve for receiving said terminal portion to effect a wobbling movement of said agitator during rotary movement of said shaft, said agitator further including a flexible sealing sleeve contiguously encircling said bearing retainer sleeve and having a depending end encompassing said bearing in said tub to provide a watertight seal for said last named bearing.

9. In a washing machine, a tub provided with a bearing therein, a wobble agitator positioned within said tub, a revoluble shaft journalled in said bearing and provided with a terminal portion inclined from the longitudinal axis of said bearing and extending into said tub, a rigid sleeve carried in said agitator for receiving said terminal portion to effect a wobbling movement of said agitator during rotary movement of said shaft, a flexible sealing sleeve joined to and depending from said agitator toward said tub, said sealing sleeve contiguously encircling said rigid sleeve and having a depending end encompassing said bearing to form a watertight seal therefor.
